SPINNING APPARATUS AND METHOD

Roland Roswell Nydegger, Wilmington, Del., assignor to E. I. du Pont de Nemours & Company, Wilmington, Del., a corporation of Delaware

Application February 18, 1939, Serial No. 257,165

13 Claims. (Cl. 18—8)

This invention relates to improvements in method and apparatus for the spinning of filaments. More particularly, it relates to an improved method and apparatus for the spinning of such filaments from molten filament-forming compositions composed largely of organic compounds.

This application is a continuation-in-part of my application, Serial No. 204,511 filed April 27, 1938.

Such filaments, and filament-forming compositions from which the filaments are formed, will hereafter be referred to as "organic filaments" or "organic filament-forming compositions."

Heretofore, in the spinning of filaments from molten organic filament-forming compositions, it was considered necessary to first melt the filament-forming composition in a suitable chamber and then force the molten mass by means of gas pressure or by means of a pump, through a suitable spinneret, or the like. Such prior art methods were suitable for use in the spinning of molten organic filament-forming compositions which were not subject to deterioration or decomposition when exposed to a melting temperature for an extended period of time.

In the melt spinning of organic filaments from solid materials, which are subject to decomposition at high temperatures, prior art methods, which involve the maintaining of the molten materials at high temperatures for extended periods of time, are objectionable.

It is an object of the present invention to provide an improved method and apparatus for the displacement spinning of filaments from molten organic filament-forming compositions.

It is a further object of this invention to provide an improved method and apparatus for the production of organic filaments from melts with a minimum exposure of the melts to high temperatures.

It is another object of this invention to provide a method and apparatus for the displacement spinning of filaments from molten organic filament-forming compositions whereby the spinning operation can be readily carried out in a continuous manner.

It is a further object of this invention to provide a method and apparatus for the displacement spinning of filaments from molten organic filament-forming compositions whereby the continuous spinning of the products can be carried out more uniformly over extended periods of time.

Other objects of the invention will appear hereinafter.

The objects of the invention may be accomplished, in general, by forcing a solid composed of an organic filament-forming composition

against a surface having an elevated temperature to melt the solid, said melted composition being forced through an opening of the desired size and shape by the oncoming solid, and collecting said filaments in any desired manner. Preferably the solid, in the form of a uniformly shaped, compact mass, is forced through an aperture into a melting chamber provided with a melting surface.

10 In order to more clearly define the present invention, reference is made to the following detailed description taken in connection with the accompanying illustrations of one modification of apparatus suitable for use in accordance with the present invention, and in which:

Figure 1 is a side elevational view, with parts shown in section, of a melting device, solid filament-forming material, sealing ring and spinneret.

20 Figure 2 is a side elevational view of an apparatus suitable for use in continuously feeding rods of filament-forming material into a melting device.

Figure 3 is a sectional view of one of the rod-feeding clamps.

Figure 4 is a sectional view taken along the line 4—4 of Figure 2.

Figure 5 is a sectional view taken along the line 5—5 of Figure 2.

30 Figure 6 is a side elevational view taken along line 6—6 of Figure 5 with parts shown in section of a portion of a rod-feeding clamp.

Figure 7 is a side elevational view, with parts shown in section, of another modification of the apparatus suitable for continuously feeding molten filament-forming material to a spinneret.

Referring to the drawings, reference numeral 1 designates a uniformly shaped and compact rod of a solid filament-forming material which is continuously forced at a constant speed through the sealing ring 3 into the melting chamber 2 by means of a constant speed, pressing member 4. The member 4 may be driven in any desired manner. As the rod 1 is forced into the melting chamber, it contacts the heated inner wall 5 of the chamber. The temperature of wall 5 is maintained somewhat above the melting point of the rod by means of heating units 6 which may be heated fluid coils, electric heating elements or any other desired heating means. The heating units 6 are enclosed by insulation 7. The solid rod of filament-forming material melts at a uniform rate as it is forced against the heating surface of wall 5 and the molten material is in

55 turn forced through channel 8 to spinneret 9 from which it issues as filaments 10 which are drawn away at a uniform speed and wound on a wind-up bobbin or the like (not shown). It has been found advantageous to pass the molten material through screen packs or filters 11 before

it is extruded through the spinneret. It has furthermore been found desirable to insulate the sealing ring 3 from the heated chamber 2 by means of insulation 12 and, if necessary, by the additional means of cooling coils, or the like, 13, thus maintaining the sealing ring 3 below the melting point of the rod of filament-forming material. If desired, the erosion of the bottom plate of insulation can be substantially eliminated by means of a metal liner 14.

It is essential for the smooth operation of the process, and for the production of filaments and yarn of uniform denier, that the rod fed to the displacement spinning unit be uniform in diameter and density. This is necessary to secure the proper seal at the sealing ring and a uniform flow of the molten material to the spinneret. Some filament-forming materials capable of being spun from melt are somewhat elastic so that the diameter of the rod, when composed of such material, should be slightly greater than the diameter of the sealing ring in order that a tight seal may be obtained. In many cases, however, the rod expands sufficiently by reason of the heat transmitted to the rod from the melt chamber so that the initial rod can be made of the same diameter or even of slightly smaller diameter than that of the sealing ring. It is advantageous to have the sealing ring slightly tapered as shown in the drawings with the larger end outermost. If desired, the end of the rod which is to be introduced into the ring may also be tapered.

The rods to be fed into the spinning unit can be prepared by any suitable means; e. g., casting, extrusion or machining. The rod should be bubble free, have a uniform density, size and shape, and be as smooth as possible. If desired, it may be covered with a lubricant; e. g., a high boiling or polymeric hydrocarbon.

Referring to the continuous feeding mechanism shown in Figures 2-6, reference numeral 20 designates a supporting frame which will be fixedly connected relative to a melting chamber such as is described with reference to Figure 1 of the drawings. A pair of collars 22 is rotatably mounted in supporting frame 20. Each of the collars 22 has a worm-driven pinion 24 keyed thereto. The pinions 24 are positioned in aligned relationship to each other so that they may be simultaneously and synchronously driven by a single worm gear or two worm gears mounted on a single drive shaft in a manner well known. The collars 22 are also keyed to their respective threaded shafts 26 whereby to rotate the latter upon rotation of the worm pinions 24. The threaded shafts 26 may, if desired, be rotatably connected to the top of melting chamber 2 of Figure 1.

One or more rod-feeding clamps 28 are positioned on the threaded shafts 26 so that they may be moved downwardly toward the melting chamber 2 upon rotation of the shafts 26 in a counter-clockwise direction. The rod-feeding clamps comprise clamping frames 30 and 32 which cooperate with the aid of screws 34 to firmly hold a rod of filament-forming material therebetween. Sleeves 36, having internal threads cooperable with the threads of shafts 26, are rotatably mounted in clamping frame 30. Worm pinions 38 are fastened to the tops of sleeves 36; the pinions 38, however, are not internally threaded and are adapted to clear the threads of shafts 26. A shaft housing 40 is attached to frame 30 by means of screws 42. A shaft 44 provided with a pair of worm gears 46

is positioned in housing 40. The gears 46 are arranged to mesh with worm pinions 38, so that upon rotation of shaft 44 the worm pinions will be simultaneously and synchronously rotated.

5 The shaft 44 is provided with a square end 48 whereby to connect to said shaft a hand crank having a similarly shaped opening.

The operation of the continuous feeding mechanism will be as follows: A rod 1 of the filament-forming material will be positioned in a rod-feeding clamp 28 and the clamping elements 30 and 32 tightened by means of screws 34. The lower end of the rod will be positioned in the sealing ring 3. The worm pinions 24 will be synchronously rotated, thereby causing shafts 26 to be rotated. The rotation of shafts 26 in a counter-clockwise direction will cause a lowering of the rod 1 and rod-feeding clamp 28. After the rod 1 has been forced into the melting chamber 2 a substantial distance and when the lowermost rod-feeding clamp 28 approaches the top surface of the melting chamber, a second rod 1a is positioned smoothly against the top of rod 1 without overlapping. A second rod-feeding clamp is fastened to the top of rod 1a. Then a hand crank (not shown) is positioned on the end 48 of shaft 44. The crank is turned clockwise to lower the upper clamp 28 until the upper rod 1a is pressed tightly against rod 1. At this point the two rod-feeding clamps will be simultaneously moved downwardly by the shafts 26 at the same speed. The lower rod-feeding clamp 28 can now be released by loosening screws 34, and by attaching the hand crank thereto and turning the same counter-clockwise, the lower clamp 28 can be moved upwardly along the shafts 26 until it touches the upper clamp 28. This cycle can be repeated indefinitely.

Figure 7 illustrates another form of apparatus 40 for the continuous melt spinning, for long periods, without interruption. This apparatus comprises two or more rod-feeding mechanisms, sealing rings, melting surfaces, etc. in communication with the spinneret. As in Figure 1, reference numeral 1 designates a uniformly shaped and compact rod of solid filament-forming material which is forced through the sealing ring 3 into the melting chamber 2 by means of a constant speed, pressing member 4. The member 4 may be driven in any desired manner. As the rod 1 is forced into the melting chamber, it contacts the heated inner wall 5 which is maintained at a temperature above the melting point of the rod by the heating units 6. The reference numerals 1', 3', 4', etc., designate an identical rod, pressing member, sealing ring, etc., respectively mounted in the same manner as that designated by 1, 3, 4, etc., and in the same melt chamber 2. The solid rods of filament-forming material melt at a uniform rate as they are forced against the heating surfaces of the walls 5 and 5' and the molten material is in turn forced into the channels 49 and 50 respectively which are provided with the valves 51 and 52 respectively, and thence through the passage 8 to the spinneret 9 from which it issues as filaments 10 which are drawn away and collected in an orderly manner. Reference numeral 12 designates a member insulating the sealing ring from the heated chamber 2, 13 designates cooling coils as additional means for maintaining the temperature of the sealing ring below the melting point of the rod and 14 designates a metal liner to prevent erosion of the bottom plate of insulation. Primed numerals designate the corresponding duplicate parts.

In the operation of this modification, the rod of solid filament-forming material 1 is used to spin filaments in the manner previously described. As the rod 1 becomes nearly exhausted, the rod 1' is brought into contact with the heating surface 5' and when melting at a uniform rate is attained the pressure on it is increased and that on the rod 1 is decreased proportionally until the transfer is completed. This transfer may be facilitated by the use of the valves 51 and 52. The valve 51 is closed and the nearly exhausted rod 1 is then replaced with a fresh rod which when the rod 1' is nearly exhausted, is brought into operation in the same manner as that described for transfer from rod 1 to 1'. If desired conduits 54 and 56 with valves 58 and 60 respectively may be provided for removing melted material during that period when a uniform melting rate is being reached, prior to changeover from one melting unit to the other. By repetition of this cycle it is possible to supply molten material to the spinneret at a uniform rate continuously for long periods. This transfer may be facilitated by the use of rod pressure mechanisms synchronized with, or directly connected to, valve opening and closing mechanisms so as to accomplish the changeover automatically.

While this modification of the invention is illustrated by the use of rods of the same diameter, it is not so limited since it is only necessary to displace a uniform quantity of molten material which can be accomplished in the case of different diameter rods by feeding at different linear speeds. Likewise, the two feeding and melting mechanisms may be mounted in separate melt chambers, or a larger number of them mounted in the same melt chamber. It is also possible to use a single auxiliary feeding and melting mechanism for a plurality of spinnerets since the time required to replace the exhausted rod is usually much less than the time in which it is consumed. Suitable valves and synchronizing mechanisms may be used to insure that the molten material is fed to the spinneret at a uniform rate.

If desired, the apparatus shown in Figure 7 may be used to feed molten material simultaneously from the duplicate assemblies. By simultaneously feeding rods of filament-forming compositions, having different properties; e. g., bright and delustered, pigmented and unpigmented or differently pigmented, having a varying dye affinity, etc., novelty yarns may be prepared.

The method and apparatus of the present invention have particular utility and advantages in the melt spinning of fiber-forming synthetic linear polyamides (superpolyamides) which may be prepared, for example, by the condensation reactions described in the U. S. patent of Carothers, No. 2,071,250. Super-polyamides are of a crystalline character and it is surprising that they can be extruded to form films and filaments in accordance with the present invention. These polyamides are of two types: those obtainable from monoaminomonocarboxylic acids or their amide-forming derivatives, including caprolactam, and those obtainable from the reaction of suitable diamines with suitable dibasic carboxylic acids or their amide-forming derivatives. The polyamides of the two types are more fully described in U. S. Patents No. 2,071,253 and No. 2,130,948 respectively. As examples of such polyamides might be mentioned polytetramethyl-

ene sebacamide, polyhexamethylene suberamide, polyhexamethylene sebacamide, polydecamethylene adipamide, and the polyamide derived from 6-amino-caproic acid. Interpolyamides and mixtures of polyamides can also be used in this invention.

These polymers, unlike most previously described filament-forming materials, are sufficiently stable to permit their spinning into filaments and the like directly from melt; i. e., without the use of solvents or plasticizing agents. The methods previously described for spinning such materials from melt consist in melting the polymer in a suitable chamber and extruding it therefrom through a suitable aperture or spinneret by means of gas pressure or by means of a pump; e. g., a constant delivery gear pump. These processes have certain disadvantages. If gas pressure is used, it is difficult to maintain constant delivery even though the gas pressure be kept constant because slow dirt collection in the spinneret packs increases the back pressure which results in a decrease in the spinneret output and in the denier of the spun material. A difficulty with the use of a spinning pump is that exposure of the moving parts of the pump to the high temperature molten filament-forming material results in short pump life. More importantly, the expansion of the pump parts at the high temperature causes pump leakage and serious variations in denier. A disadvantage of both methods is that the filament-forming material must be heated considerably above its melting point to secure smooth spinning. This frequently results in thermal decomposition of the filament-forming material with the formation of gaseous or other undesirable by-products. Furthermore, a considerable reservoir of the filament-forming material must be kept in the molten state to maintain uniform spinning which further promotes thermal decomposition. These disadvantages are overcome by the process and apparatus of the present invention.

The process will now be described more specifically with reference to polyhexamethylene adipamide, a fiber-forming linear condensation polyamide derived from the condensation polymerization of hexamethylene diamine and adipic acid.

Example

A uniform cylindrical rod of polyhexamethylene adipamide having a diameter of 2.00 inches and a height of 12 inches was prepared by extruding molten polymer having an intrinsic viscosity of 0.9 and a melting point of about 263° C. from an autoclave under 100-lb. oxygen-free nitrogen pressure into an electrically heated casting tube against a downward moving piston, and cooling the tube while maintaining the same under pressure. The smooth rod thus formed was readily removed from the tube by means of the piston. This rod was then machined to a perfect cylinder and fed into a displacement spinning unit of the type shown in the drawing, mounted in an Olsen testing machine where advantage could be taken of both the uniform feed and the balance to measure the pressures applied to the mechanism. The rod was forced through the sealing ring and against the melting surface of the melting chamber under a total pressure of 2,500 lbs., of which approximately 400 lbs. represents the resistance through the sealing ring. The melting surfaces were maintained at about 275° C. The spinneret employed

contained 30 openings, each 0.0088 of an inch in diameter. Under these conditions, 30-filament yarn of fairly uniform denier (discounting that spun during the first few minutes) was spun at a rate of about 13.5 grams per minute. The yarn was wound up on a bobbin at a rate of 2,000 feet per minute.

Although the foregoing example illustrates the invention with specific reference to a synthetic polyamide, it will be apparent that the process can be applied to other materials. The invention is applicable to the spinning of any organic filament-forming material which is capable of being spun from melt. As examples of such filament-forming materials may be mentioned polymers obtainable by the high pressure polymerization of ethylene, polystyrene, and polyacrylic acid derivatives. Other types of fiber-forming synthetic linear polymers (super-polymers); e. g., the polyesters, polyethers, polyacetals, and mixed polyester-polyamides described in U. S. Patent No. 2,071,250 may also be used. Cellulose derivatives; e. g., cellulose acetate, if suitably plasticized can also be spun by this method. If the mechanical characteristics of the rod are such as to require it, the rod may be supported by a reinforcing cylinder, in which case the pressing member will ride in the cylinder, and the latter may, in such a modification, function in the capacity of a sealing ring.

The filament-forming material used in the process of this invention may contain modifying agents; e. g., luster-modifying agents, plasticizers, pigments, dyes, antioxidants, resins, etc.

The example illustrates the application of this invention to the preparation of a yarn. On subjecting this yarn to cold drawing, it is converted into a yarn of smaller denier and improved properties, which is very useful in making fabrics. It is within the scope of this invention to make larger diameter filaments; e. g., those of bristle, mohair or horsehair size. These large filaments can be spun from multiple hole spinnerets or from single hole spinnerets. Likewise, a plurality of spinnerets may be fed by a single melting assembly. Ribbons, foils, sheets, etc. can also be prepared by displacement spinning. For this purpose it is usually desirable to extrude the filament-forming material through a slit orifice and/or collect the product on a suitable forming roller or rollers to secure the proper uniformity.

By practice in accordance with the present invention, it is possible to extrude a filament-forming material at an exceptionally constant and uniform rate. Therefore, by withdrawing the extruded filaments at a uniform rate, it is possible to obtain filaments and yarns of very uniform denier. The process has the following advantages over previously described methods of melt spinning:

- (1) Minimum exposure of the filament-forming material to high temperatures.
- (2) Complete elimination of a gas blanketing agent in the melt chamber.
- (3) Melt chamber is self-cleaning.
- (4) Less screen packing is necessary, since the danger of small pieces of unmelted material in the molten mass is minimized.
- (5) By forcing a uniformly shaped, compact rod of a filament-forming material through an aperture, such as a sealing ring, into a melting chamber, the spinning process can be made continuous by following one rod with another without stopping the spinning operation.
- (6) By combining a screen pack or filter with

the above process of forcing a solid rod of filament-forming material through a melting chamber, it is possible to extrude continuously for long periods of time with exceptionally uniform results. Greater uniformity of filament denier is obtainable since a specific volume of filament-forming material is displaced, regardless of the increase in resistance resulting from accumulation of dirt on the screen pack.

(7) There will be a reduction of surface dirt on the filament-forming material because of the more favorable ratio of area to volume of the raw material. In other methods, the filament-forming material is usually added to the melting chamber in finely divided form.

(8) By the present process, pumps and other moving parts, which would ordinarily be in continuous contact with the molten material, are eliminated.

Since it is obvious that many changes and modifications of the above process and apparatus can be made without departing from the nature and spirit of the invention, it is to be understood that the above description is not to be limited except as set forth in the appended claims.

I claim:

1. In an apparatus for the melting of uniformly shaped solid rods of organic filament-forming compositions and the forming of filaments from the melted compositions, a plurality of spaced melting surfaces, a sealing ring connected to each of said melting surfaces, said sealing rings serving as entrances for said rods to said respective melting surfaces, at least a section of each of said sealing rings having an internal dimension smaller than the cross-sectional dimension of said rods, positively driven means for forcing said rods through one of said sealing rings at a uniform rate against the corresponding melting surfaces, conduit means from each of said melting surfaces to a common outlet, and a shut-off means in each of said conduit means.

2. In an apparatus for the melting of uniformly shaped solid rods of organic filament-forming compositions and the forming of filaments from the melted compositions, a plurality of spaced melting surfaces, a sealing ring connected to each of said melting surfaces, said sealing rings serving as entrances for said rods to said respective melting surfaces, at least a section of each of said sealing rings having an internal dimension smaller than the cross-sectional dimension of said rods, positively driven means for forcing said rods through one of said sealing rings at a uniform rate against the corresponding melting surfaces, an extrusion orifice, conduit means from each of said melting surfaces to said extrusion orifice, and a shut-off means in each of said conduit means.

3. In an apparatus for the melting of uniformly shaped solid rods of organic filament-forming compositions and the forming of filaments from the melted compositions, a plurality of spaced melting surfaces, a sealing ring connected to each of said melting surfaces, said sealing rings serving as entrances for said rods to said respective melting surfaces, at least a section of each of said sealing rings having an internal dimension smaller than the cross-sectional dimension of said rods, positively driven means for forcing said rods through one of said sealing rings at a uniform rate against the corresponding melting surfaces, an extrusion orifice, conduit means from each of said melting

surfaces to said extrusion orifice, and a shut-off means in each of said conduit means, and means between said melting surfaces and said extrusion orifice for withdrawing molten composition from each of said melting surfaces.

4. In an apparatus for the forming of filamentous structures from melts of organic filament-forming compositions, a melting chamber, a sealing ring connected to said melting chamber, said sealing ring having walls converging inwardly towards the interior of said chamber, a spinneret in said chamber, and means for forcing a uniformly shaped, solid mass of the filament-forming composition through said ring into said chamber whereby to melt said material and force the molten material through said spinneret.

5. In an apparatus for the forming of filamentous structures from melts of organic filament-forming compositions, a melting chamber, a sealing ring connected to said chamber, a spinneret in said chamber, means for forcing a uniformly shaped, solid mass of the filament-forming material through said ring into said chamber whereby to melt said material and force the molten material through said spinneret, and a filtering means in said chamber between said sealing ring and said spinneret.

6. The method of forming filaments from melts of organic filament-forming compositions of crystalline character which comprises forcing a solid, uniformly shaped rod composed of said composition through an aperture of smaller cross-sectional dimension than said rod and against the solid surface of an element having an elevated temperature to melt only that portion of the rod adjacent said surface, and forcing said melted composition from said surface and through an opening of the desired shape by pressure of the oncoming solid rod.

7. The method of forming filaments from melts of synthetic linear polymers which comprises forcing a solid, uniformly shaped rod composed of said polymer through an aperture of smaller cross-sectional dimension than said rod and against the solid surface of an element having an elevated temperature to melt only that portion of the rod adjacent said surface, and forcing said melted polymer from said surface and through an opening of the desired shape by pressure of the oncoming solid rod.

8. The method of forming filaments from melts of organic filament-forming compositions of crystalline character which comprises forcing a solid, uniformly shaped rod composed of said composition through an aperture of smaller cross-sectional dimension than said rod and against the surface of an element having an elevated temperature to melt only that portion of the rod adjacent said surface, and forcing said melted composition through a filtering medium and through an opening of the desired shape by pressure of the oncoming solid rod.

9. The method of forming filaments from melts of organic filament-forming compositions of crystalline character which comprises forcing at a substantially constant, uniform rate, a successive series of solid, uniformly shaped rods composed of said composition through an aperture of smaller cross-sectional dimension than said rods and against the solid surface of an element having an elevated temperature to melt

only that portion of the rods adjacent said surface, and forcing said melted composition from said surface and through an opening of the desired shape by pressure of the oncoming solid rods.

5 10. In an apparatus for the melting of a series of uniformly shaped solid rods of organic filament-forming compositions and the forming of filaments from the melted compositions, a melting chamber having a solid melting surface therein, a sealing ring connected to said melting chamber, at least a section of said sealing ring having an internal dimension smaller than the cross-sectional dimension of said rods, and positively driven means for forcing, at a substantially constant, uniform rate, said series of rods through said sealing ring and against said melting surface.

11. In an apparatus for the melting of a series 20 of uniformly shaped solid rods of organic filament-forming compositions and the forming of filaments from the melted compositions, a melting chamber having a solid melting surface therein, a sealing ring connected to said melting 25 chamber, at least a section of said sealing ring having an internal dimension smaller than the cross-sectional dimension of said rods, a spinneret in said chamber, a plurality of members adapted to be clamped on said rods, and means 30 for moving said members toward said melting surface at a constant, uniform rate for forcing said series of rods through said sealing ring and against said melting surface and forcing the melted composition through said spinneret.

35 12. In an apparatus for the melting of a series of uniformly shaped solid rods of organic filament-forming compositions and the forming of filaments from the melted compositions, a melting chamber having a solid melting surface therein, a sealing ring connected to said melting chamber, at least a section of said sealing ring having an internal dimension smaller than the cross-sectional dimension of said rods, and means 40 for continuously forcing a successive series of rods at a substantially constant, uniform rate through said sealing ring and against said melting surface, said means comprising a plurality of rod clamping members, means for forcing said members toward said melting surface, and means for shifting said members along said forcing means.

13. In an apparatus for the melting of a series 55 of uniformly shaped solid rods of organic filament-forming compositions and the forming of filaments from the melted compositions, a melting chamber having a solid melting surface therein, a sealing ring connected to said melting chamber, at least a section of said sealing ring having an internal dimension smaller than the cross-sectional dimension of said rods, a series 60 of positively driven rod clamping members, screw means for continuously forcing said rod clamping members toward said melting surface, and means for shifting said rod clamping members along said screw means, whereby to force a successive series of rods at a substantially constant, uniform rate through said sealing ring and against said melting surface.

CERTIFICATE OF CORRECTION.

Patent No. 2,253,089.

August 19, 1941.

ROLAND ROSWELL NYDEGGER.

It is hereby certified that error appears in the printed specification of the above numbered patent requiring correction as follows: Page 4, second column, lines 38, 55, and 72, claims 1, 2, and 3 respectively, strike out the words "one of"; page 5, second column, line 7, claim 10, for "pods" read --rods--; and that the said Letters Patent should be read with this correction therein that the same may conform to the record of the case in the Patent Office.

Signed and sealed this 7th day of October, A. D. 1941.

(Seal)

Henry Van Arsdale,
Acting Commissioner of Patents.
